UNITED STATES PATENT OFFICE

ANDREW FORREST, OF CHICAGO, ILLINOIS, ASSIGNOR, BY MESNE ASSIGNMENTS, TO REPUBLIC STEEL CORPORATION, OF YOUNGSTOWN, OHIO, A CORPORATION OF NEW JERSEY

HEADER FOR INGOT MOLDS

Application filed December 12, 1927, Serial No. 238,300. Renewed December 30, 1929.

My invention relates to ingot casting and particularly to mold headers or hot-tops which are formed or provided with refractory non-conducting inner walls or linings to conserve the heat of the metal therein while solidification of the metal in the mold occurs, so that the header metal supplies or fills the pipe cavity formed in the mold metal by shrinkage or segregation while solidifying.

10 In headers now in general use the refractory material is rapidly destroyed by the abrasive action of the molten metal flowing through the header into the mold and by the sticking of the metal to the refractory material, particularly in its corners; the metal as it is poured through the header into the mold cuts and abrades this material and wears it away; the metal also works into this material and into the joints where fire-bricks are used 15 and fills its depressions, interstices and rough surfaces so that it sticks to the header, and when the metal shrinks in solidifying and the header is stripped from the sink-head the refractory material is disintegrated, pitted or 20 broken at one or more places. The result has been that such headers lasted at times for only a single heat or the casting of one ingot, and at best required renewal of the lining or substitution of a new header after very few 25 heats; in either case the cost of hot-top maintenance and operation, and hence of ingot production, is considerably increased.

The objects of my invention are to minimize the abrasive and sticking actions of the 30 metal on the header wall, and to reduce its normal wear, and thereby increase the number of heats that a header will run. With these objects in view my invention consists in general in providing the header wall with a 35 facing or coating of non-carbonaceous refractory material.

My invention may be embodied in various 40 forms of headers, and practical exemplifications are shown for illustrative purposes in the accompanying drawings, in which Fig. 1 is a vertical central sectional view through the top of an ingot mold equipped with a header having a passage of circular cross-section; Fig. 2 is a top plan view of the header shown 45 in Fig. 1; Fig. 3 is a similar view of a header

having a passage of octagonal cross-section; and Fig. 4 is a view like Fig. 1 with the header shown in Fig. 3 seated on the mold.

In the drawings the reference numeral 1 indicates an ingot mold of suitable size and 55 shape, and 2 a metallic header-casing which when in use rests on the upper end of the mold and is open-ended and is of any desired cross-sectional contour; in Fig. 2 the casing is shown as circular and in Fig. 3 as octagonal. 60 The casing 2 is usually tapered upwardly and may be provided with lifting-ears 3 and with a lining-seat 4 at its lower end which may be formed as an integral ledge as in Fig. 1 or as a separate ring as in Fig. 4 or may be 65 omitted. The header wall or lining is of any suitable heat-insulating refractory material 5, preferably fire-bricks, and forms a passage for the molten metal being poured into the associated mold and a receptacle for a suitable amount of sink-head metal. This passage is of any suitable contour and usually is conical or tapered upwardly to facilitate the subsequent stripping of the header from the cooled ingot end or sink-head by lifting 70 or pulling it off. The parts so far described may be of any suitable material, form and organization, and may be varied in these respects in accordance with the requirements of any desired equipment, as the present invention 75 may be exemplified or embodied in hot-tops or headers of different types and constructions.

The inner wall of the hot-top is provided 80 with a facing or coating 6 of non-carbonaceous material, composed of a suitable pulverized refractory material, preferably of relatively high-refractory quality, such for example as fire clay, ganister, fire-brick, silica sand or chrome ore, and a suitable binder, 85 such for example as molasses mixed with water. In commercial practice I have successfully employed a compound of two hundred and forty (240) pounds of silica fire-clay and two (2) quarts of molasses mixed 90 with sufficient water to form a plastic or slush mixture. I have mixed the above amounts of fire-clay and molasses with fourteen and one-half (14½) quarts of water and formed 95 a mortar-like plastic mixture which was 100

easily spread on the wall and proved particularly useful and effective where the surface was abraded, pitted or broken, as it plastered up large holes and deeply worn places and 5 restored the shape and smoothness of the surface. In other cases where the inner wall was not so seriously damaged by the metal, as where it had merely crumbled or disintegrated under the normal wear and tear 10 incident to employing the header, I have used more water to thin the above mixture to the consistency of paint, and the slush or slurry so formed when brushed or painted onto the wall successfully repaired such disintegrated 15 and worn places. The proportions of the constituents may be varied within limits which provide a mixture than can be spread on the inner wall and forms thereon an adhesive coating or facing of non-carbonaceous refractory material. In practice I apply a suitable coating of the mixture to the inner wall 20 of the header before it is used, and between heats when required; and preferably I also brush or wipe the plastic coating with the 25 slurry to dress or finish it off to a smoother surface. The mixture penetrates more or less into the heat-insulating material 5 and fills all irregularities, interstices and cavities in it and any joints between its sections or bricks, 30 and when dry cements and binds the bricks or sections together and forms a hard protective coating therefor. When the molten metal is run into the mold the facing or coating protects the material 5 from the cutting or 35 abrasive action of the flowing metal; this action occurs primarily and generally wholly in the coating and is correspondingly taken away from the material 5 and minimized therein. Also, the facing or coating prevents 40 the metal from working into the material 5 or into the joints of its bricks or sections, and so prevents the metal from sticking to the wall of the header. Any sticking action of the metal occurs between it and the coating, 45 and if the latter sticks to the metal it comes away free from the material 5 when the header is separated or stripped from the sink-head or ingot and so enables the header to be stripped without serious injury to the material 5, frequently caused by pitting and 50 fracturing, and it also reduces the normal wear of the material 5 caused by its liability to crumble or disintegrate. When the coating material sticks to the metal in the stripping 55 operation it can be easily and quickly repaired or renewed by wiping or painting the slurry mixture onto the wall. My invention increases the number of heats that the headers will last; they have averaged in com- 60 mercial work for casting more than fifty (50) ingots and have frequently lasted for casting between seventy (70) and eighty (80) ingots before renewal of the insulating material 5 was necessary. Thus fewer headers are re- 65 quired to carry on the casting operation and

enable the molds to be utilized continuously and the metal to be poured into them for successive heats before they are cold, the frequency of relining the headers is lessened, and the time and labor required to reline them is greatly reduced. My invention effects economy in capital investment, time and labor, and reduces the cost of operation and maintenance of hot-top conditions. Also, the non-carbonaceous property of the coating prevents the metal from taking up any carbon and so does not affect the composition of the ingot; any of the coating material carried into the mold by the metal floats as slag on top of the sink-head metal in the hot-top and so does not mix with the ingot-metal, whereas as plumbago or carbon is taken up by steel and mixes with it, and this objection is obviated by my invention. 70 75 80

In practice I prefer to embody my invention in headers or hot-tops having substantially circular inner walls or bores decreasing in diameter upwardly and formed of longitudinally extending fire-bricks, such as shown for example in Fig. 2, as this organization affords advantages in applying the protective mixture to form a circular passage and in reducing the tendency of the metal to stick to the facing or coating and the resulting wear of the latter. 85 90 95

My coating when dry forms a smooth, hard and highly refractory layer which resists the eroding and spalling action of the hot metal, it binds the lining bricks together and greatly increases the resistance or insulation of the lining against heat-radiation whereby the header metal's fluidity to feed the ingot pipe is prolonged, and it is not readily disintegrated by the high heat of the ingot metal; and these characteristics and advantages persist for many heats or pourings in commercial ingot casting. And as my coating does not extend below the lining on the supporting ledge it is not liable to come in contact with the mold and be broken in assembling and disassembling the headers and molds; and its hard, smooth surface affords easy stripping of the header-metal when cool. 100 105 110 115

I claim:

1. A hot-top for an ingot mold having a lining of fire-brick, and a non-carbonaceous coating on the inner wall of the lining composed of fire clay and a binder. 115
2. A hot-top for an ingot mold having a lining of fire-brick, and which has its inner wall coated with a non-carbonaceous material formed by a mixture of approximately two hundred and forty pounds of fire-clay, two quarts of molasses and fourteen and one-half quarts of water. 120
3. A hot-top for ingot molds comprising a metal casing adapted to rest on the upper end of a mold, a lining of fire-bricks for the casing forming a tapered passage substantial- 130

- ly circular in cross-section, and a coating of fire-clay on the inner surface of the lining forming a circular wall on the tapered passage.
5. A hot-top for an ingot-mold having a lining of fire-brick and an inner non-carbonaceous coating formed by a mixture of approximately two hundred and forty pounds of heat-insulating refractory plaster material and a suitable binder.
10. 5. A hot-top for ingot molds comprising a metal casing adapted to rest on the upper end of a mold, a lining of fire-bricks in the casing forming a tapered passage, and an inner plaster coating of non-carbonaceous refractory material binding the bricks together and forming a circular wall on the tapered passage.
15. 6. A header for ingot molds comprising a tapered casing having an inner ledge, a lining composed of a plurality of elongated refractory sections supported on the ledge and extending longitudinally of the casing and forming a tapered passage, and a coating forming a substantially circular wall on the lining and consisting of a plaster layer of non-carbonaceous refractory material and an inner slurry layer of similar material.

In testimony whereof I affix my signature.
